(57) **CLAIM**

The ornamental design for an outdoor lighting fixture, as shown and described.

DESCRIPTION

FIG. 1 is a front elevation view of the design, a rear elevation view being the mirror image thereof;
FIG. 2 is a left side elevation view thereof;
FIG. 3 is a right side elevation view thereof; and,
FIG. 4 is a top plan view thereof.

The broken lines shown are for illustrative purposes only and form no part of the claimed design. The outdoor lighting fixture is shown broken away in FIGS. 5-7 to indicate indeterminate height.
